UNITED STATES PATENT OFFICE

172,875

TORCHÈRE

Ben Glassman, Chicago, Ill., assignor to Rembrandt Lamp Corporation, Chicago, Ill., a corporation of Illinois

Application October 7, 1953, Serial No. 27,097

Term of patent 7 years

(Cl. D48—20)

To all whom it may concern:

Be it known that I, Ben Glassman, a citizen of the United States and resident of Chicago, in the county of Cook and State of Illinois, have invented a new, original, and ornamental Design for a Torchère, of which the following is a specification, reference being had to the accompanying drawing, forming a part hereof.

Fig. 1 is side perspective view of a torchère showing my new design; and

Fig. 2 is a top plan view thereof.

I claim:

The ornamental design for a torchère, substantially as shown.
